FUNNEL GUIDE MOUNTING

Hobart O. Davidson, Swarthmore, Pa., assignor to
 American Viscose Corporation, Wilmington,
 Del., a corporation of Delaware

Application May 16, 1945, Serial No. 594,096

6 Claims. (Cl. 57—76)

1

This invention relates to an improved funnel guide mounting. More particularly the invention relates to a mounting for the funnel through which filamentary material, produced in accordance with the viscose process, for example, may be led into a spinning bucket in which it is collected in the form of an annulus.

The invention is concerned especially with funnel mountings of the type shown in Rushton 1,672,691 adapted to swing the funnel into operative position in the spinning bucket, and to swing the funnel clear of the bucket when a "cake" of filamentary material collected therein is ready for doffing.

The type of mounting of which the present invention is an improvement comprises a support adapted to be secured to the traverse rail of a spinning machine, means for holding the funnel, and two parallel pairs of arms arranged between the support and funnel-holding means, and pivotally connected to each of them. In funnel mountings of the general type described which have been available prior to the present invention, the arms connecting the support and funnel-holding means have been pivotally mounted on the support and holding means by pivots which also constitute part of the means for adjusting the tightness of the joints between the arms and the connected parts. In addition, such adjusting means have been located in exposed positions where they have been subject to corrosion by the acid escaping from the spinning machine.

Experience has shown that because of the corrosive effects of the acid in the neighborhood of the machine, the joints of the funnel-mountings sometimes tend to become stiff and unworkable after only short periods of use, and require constant readjustment. Further, since the pivots and adjusting means are interdependent, the constant swinging of the arms on their pivots has a loosening effect on the joints so that when the parts are not used under corrosive conditions and sometimes even when used under such conditions, retention thereof in a predetermined tight but relatively movable condition frequently requires readjustment.

It is a primary object of the present invention to provide a swingable funnel mounting which functions smoothly and maintains its tightness at all times over long periods of use. Another object is to provide a funnel mounting of the type described in which the means for tightening the joints is independent of the pivotal means connecting the pairs of parallel arms to the sup-

2

port and to the funnel-holding means and the surfaces of the joints, between which the adjustable predetermined pressure is exerted to control the ease of relative motion at the joints, are situated well within the joint so that the parts of the joint protect these surfaces from the influence of foreign matter and corrosion, thereby minimizing any tendency of the parts of the joint to bind or to become substantially more difficult to move during periods of operation when exposed to such influences. Other objects and advantages of the invention will be apparent from the following description when read in conjunction with the accompanying drawing, in which—

15 Figure 1 is a side elevation of the improved funnel mounting, in which the operative position is shown in solid lines, and the inoperative position is shown in broken lines;

20 Figure 2 is a plan view of the improved mounting;

Figure 3 is a view taken on line III—III of Figure 2;

Figure 4 is a detail view of a modified joint; and

25 Figure 5 is a view showing a modified pin on a somewhat enlarged scale.

In the drawing there is shown a portion of a spinning bucket 2 provided with a cover 3. A traverse rail 4 is provided to impart relative vertical reciprocal movement between the spinning bucket 2 and the funnel guide 5 for laying the filamentary material in a series of layers against the inside wall of the bucket. The filamentary material is introduced into the bucket through

30 funnel 5 having a stem 6 extending into the bucket through aperture 7 in cover 3. The holding means for the guide 5 comprises a threaded bushing 12, an extension 9 of a movable member 10, and the nuts 8 for adjustably holding the guide and bushing in fixed position on the extension 10. Secured to traverse rail 4 by bolts

35 13 is a support 14.

Support 14 is connected with movable member 10 of the funnel-holding means by two pairs of arms 15 arranged in parallel relation one pair above the other, each pair of arms being pivotally connected to support 14 and movable member 10 by means of pivot pins 16. The pins 16

40 may extend from bosses or equivalent parts of the movable member 10 and the support 14 into bores within the arms 15, as shown, or they may extend from the arms 15 into recesses formed within the movable member 10 and the support 14. However, each pin 16 has an end bearing

45 surface comprising a surface of revolution whose

50 55

55

generatrix is inclined to the axis, preferably conical as shown at 17 in Figures 1 and 2, or spherical, as shown at 17b in Figure 5, which engages a mating end surface of the bore, such as those in the arms 15, into which the pins extend, this engagement leaving clearances (clearly shown in Figure 2) around the pins 16 between the ends of the arms 15 and the adjacent faces of support 14 as well as the adjacent faces of the member 10, thereby avoiding the exertion of any pressure between the faces of the arms and the adjacent faces of the movable member 10 and the support 14. The use of a spherical or conical bearing surface also assures true and accurate positioning of the parts and the maintenance of such positioning even when light pressure only is placed upon such bearing surfaces.

The two arms 15 constituting each pair are adjustably joined together by shouldered studs 18 which screw into threaded holes 19 in the inner faces of the arms. The ends of the studs are threaded oppositely; that is, one end is left-hand and the other right-hand so that turning of the knurled portion intermediate the shoulders tightens or loosens the connection between the stud and the pair of arms. Gaskets 20 such as of rubber, may be provided between the arms 15 and the shoulders of studs 18. Studs 18, which in co-operation with the threaded holes in the sides of the arms afford a ready means of simultaneously adjusting the relation of the arms 15 to set the joints in any desired tightness, are disposed intermediately of and independently of the pivot pins 16 whereby the arms are connected to support 14 and member 10. The studs are readily available for adjustment by the operator.

The pivotal movement of the arms on the support 14 and member 10 of the funnel-holding means does not affect the studs or exert friction thereon, causing undue wear or loosening thereof, and the parts are retained in the adjusted position until changed by the operator. The bearing surfaces 17 of the pivot pins which control the ease of manipulation of the joint are entirely enclosed within the arms or within support 14 and member 10 and are not affected by acid escaping from the spinning machine, so that the arms remain as freely swingable as when originally adjusted over an indefinite period of time and the funnel mounting does not become stiff or unworkable. The funnel mounting may be constructed in its entirety of any suitable acid-resisting material, such as a resinous material of the type of Bakelite or Durez, for instance and, preferably, pivot pins are molded or otherwise formed integrally with the arms 15 or members 10 and 14.

Figure 4 illustrates a modified joint in which the pivot pin 16a extends from the inner surface of arm 15 into a bore within the member 10 (or support 14). The pin 16a has a flat end surface 17a which bears against a corresponding flat bottom surface at the end of the bore, leaving a clearance between the adjacent surfaces on arm 15 and member 10 (or support 14). The flat surface 17a may be considered a surface of revolution generated by a line inclined at right angles to the axis. If desired, a smaller bore or recess 16b may be made in the end of the large bore to facilitate separation of the parts when it is desired to dismantle the mounting structure. Figure 5 shows a pin 16 having an end bearing surface 17b of spherical character.

Modifications may be made in the apparatus

disclosed herein without departing from the spirit and scope of the present invention which is not to be limited except as necessitated by the appended claims.

5 I claim:

1. A guide mounting comprising means for holding the guide, a support, and at least one pair of arms arranged therebetween in parallel relation, pivotal means connecting adjacent ends of the arms with the support and additional pivotal means connecting the other adjacent ends of the arms with the guide holding means, each of said pivotal means comprising a pin extending into a bore and having a bearing surface comprising a surface of revolution whose generatrix is inclined to the axis of the pin in engagement with a corresponding bearing surface within the bore and clearances around the pins and disposed between the support and the adjacent ends of the arms and between the guide holding means and the adjacent ends of the arms, and means independent of the pivotal connections disposed intermediately of each pair of arms for adjustably joining the arms of a pair together.

2. A guide mounting comprising means for holding the guide, a support, and at least one pair of arms arranged therebetween in parallel relation, pivotal means connecting adjacent ends of the arms with the support and additional pivotal means connecting the other adjacent ends of the arms with the guide holding means, each of said pivotal means comprising a pin extending into a bore and having a terminal bearing surface comprising a surface of revolution whose generatrix is inclined to the axis of the pin in engagement with a corresponding bearing surface within and adjacent the bottom of the bore and clearances around the pins and disposed between the support and the adjacent ends of the arms and between the guide holding means and the adjacent ends of the arms, and means independent of the pivotal connections disposed intermediately of each pair of arms for adjustably joining the arms of a pair together.

3. A guide mounting comprising means for holding the guide, a support, at least one pair of arms arranged therebetween in parallel relation, pivotal means adjacent ends of the arms with the support and additional pivotal means connecting other adjacent ends of the arms with the guide holding means, each of said pivotal means comprising a pin extending into a bore and having a bearing surface comprising a surface of revolution whose generatrix is inclined to the axis of the pin in engagement with the corresponding bearing surface within the bore and clearances around the pins and disposed between the support and the adjacent ends of the arms and between the guide holding means and the adjacent ends of the arms, means disposed intermediately of and independently of the pivotal means for adjustably connecting the arms of each pair together, said connecting means comprising oppositely threaded studs co-operating with correspondingly threaded bores in the arms.

4. A guide mounting comprising means for holding the guide, a support, two pairs of arms arranged therebetween in parallel relation one pair above the other, pivotal means connecting adjacent ends of the arms with the support and additional pivotal means connecting the other adjacent ends of the arms with the guide holding means, each of said pivotal means comprising a pin extending into a bore and having a conical bearing surface adjacent its end in engagement

with a corresponding conical bearing surface adjacent the bottom of the bore and clearances around the pins and disposed between the support and the adjacent ends of the arms and between the guide holding means and the adjacent ends of the arms, and means independent of the pivotal connections disposed intermediately of each pair of arms for adjustably joining the arms of a pair together.

5. A guide mounting comprising means for holding the guide, a support, two pairs of arms arranged therebetween in parallel relation one pair above the other, pivotal means connecting adjacent ends of the arms with the support and additional pivotal means connecting the other adjacent ends of the arms with the guide holding means, each of said pivotal means comprising a pin extending into a bore and having a spherical bearing surface adjacent its end in engagement with a corresponding spherical bearing surface adjacent the bottom of the bore and clearances around the pins and disposed between the support and the adjacent ends of the arms and between the guide holding means and the

10

15

20

adjacent ends of the arms, and means independent of the pivotal connections disposed intermediately of each pair of arms for adjustably joining the arms of a pair together.

6. A guide mounting comprising means for holding the guide, a support, two pairs of arms arranged therebetween in parallel relation one pair above the other, pivotal means connecting adjacent ends of the arms with the support and additional pivotal means connecting the other adjacent ends of the arms with the guide holding means, each of said pivotal means comprising a pin extending into a bore and having a flat bearing surface adjacent its end in engagement with a corresponding flat bearing surface adjacent the bottom of the bore and clearances around the pins and disposed between the support and the adjacent ends of the arms and between the guide holding means and the adjacent ends of the arms, and means independent of the pivotal connections disposed intermediately of each pair of arms for adjustably joining the arms of a pair together.

HOBART O. DAVIDSON.
